Ms. 1227

Charles Müller, of New York, N. Y.
assigns to John Matthews, of same place,
Letters Patent No. 1227, dated April 3, 1860.

22

Des. 1227

The Schedule referred to in these Letters Patent and making part of the same

To all whom it may concern:

Be it known that I, Charles Miller, of the City, County and State of New York, have invented or produced a new and original design for a Water Cooler, and I do hereby declare that the following is a full, clear and exact description of the same, reference being had to the annexed drawing, being an Elevation of Water Cooler showing my design.

The main portion or body A. of the cooler is of cylindrical form provided at two opposite points with handles B. B. in the form of the heads and necks of top-knot ducks, which project horizontally from the body A. On the body A. there is also a basso-relievo C. representing Cupid guiding a polar bear, with appropriate scenery in the distance.

The body A. has a rope moulding a. at its lower part, said moulding being immediately above a large inclined or ovoli quirked moulding D. having leaves b. upon it, side by side. The moulding D. rests on a cylindrical base E. which has a scroll and leaf ornament c.

The upper part of the body A. also has a rope moulding d. above which there is a larger and more open rope moulding e. The latter having above it a concave moulding f. surmounted by a curved or convex rim g. which has leaves upon it, side by side similar to the moulding D.

F. is the cover, a vertical section of which presents a double ogee or cymatium form. This cover has an ornament h. upon it formed of scrollis & leaves. The cover is surmounted by a pelican and young b.

I claim the cylindrical body A. with the configuration of the handles B. basso-relievo C. base E. mouldings D. a. d. e. f. g. h. and cover F. all forming a new and original design for a Water Cooler.
